UNITED STATES PATENT OFFICE

1,971,281

DISPLAY DEVICE

Frank J. Sprague, New York, N. Y.

Application January 30, 1933, Serial No. 654,319

16 Claims. (Cl. 40—84)

My invention relates to a novel display device as well as to a method of operation, by which a plurality of display members, for instance, lithographed posters, photographs or 5 other forms of advertisements are made up into an assembly and are successively displayed in an opening or window of the casing of the display device.

I shall describe my invention on hand of a 10 preferred embodiment, which consists of a sectioned elastic belt or band made up of a series of individual and independent display units, each of which includes a carrier provided with guide extensions, and with a freely turning 15 spring-biased roller to which the display member, for instance, a poster, is detachably anchored with one of its ends. When the different units are assembled into a band the free end of each poster is detachably locked to the carrier 20 of the next unit in advance, or in the rear.

The housing of the display device is provided 25 on the inside of each of the two opposing sides with tracks of like contour, in which tracks the guide extensions of the display units are preferably guided. The tracks preferably form loops in which the display units are spaced with the posters in rolled up, or partly or fully unwound condition depending on the position of their 30 units in the tracks.

30 The units may be removed or inserted from either the front or the back of the display device, and the number of units can be increased or decreased within the maximum and minimum capacity of the track, whereby the display band 35 will automatically adjust itself to the number of units installed.

The displays may be progressed continuously, but preferably by interrupted advance past the 40 frontal window or frame, and while before the window the posters unroll from their roller and when fully unrolled before the display window the poster is stopped, although the driving mechanism and driving members for the carriers are rotating at continuous speed.

45 For the advance of the carrier members I provide preferably carrier chains mounted on the two opposing sides of the housing of the display device and close to the tracks. The chains are suitably driven by motor and intermediate 50 driving members, and carry pick-up links which engage the carriers of the units for their passage before the display window and disengage the carriers after they have passed the window.

55 My novel display device comprises various important advantages, for instance, standard ad-

vertising posters may be used. The number of posters can be varied between the maximum and minimum capacity of the device.

The insertion and removal of one or all of the units requires but little time and skill.

60 My novel device comprises few, simple and rugged parts, can be manufactured at comparatively low cost, and the mechanism requires practically no servicing.

The whole device forms a self-contained unit and the insertion and removal of the units can take place by opening the display window carrying front frame of the housing.

The device can be manufactured in various sizes whereby to a great extent the same standard parts can be used also for different sizes.

70 Except for the poster and for the carrier bar, which may also be provided with advertising matter—no part of the device passes the display window, and the printed matter of the displays 75 appears before the window in such a manner that the successive lines can be read in the natural way.

The poster can be conveniently and efficiently 80 illuminated from the inside and no part of the device falls between the light source and the poster.

Various other novel features and advantages 85 of my invention will appear as the specification progresses.

In the drawings forming part of the specification:

Figure 1 is a front view, partly broken away, 90 of a sign display device according to my invention.

Fig. 2 is a section of Fig. 1 along the line 2—2.

Fig. 3 is an enlarged section, partly broken away, of Fig. 1, along the line 3—3.

Fig. 4 is a partly broken away, enlarged view of 95 the right front end of Fig. 1.

Fig. 5 is a front view of a display unit with its poster unwound and connected to the carrier of the preceding unit.

Fig. 6 is a side view of Fig. 5.

Fig. 7 is a side view of the display unit seen 100 from the left.

Fig. 8 is a fractional perspective view of the upper end of the poster.

Fig. 9 is a fractional perspective view of the 105 lower end of a poster.

Fig. 10 is a perspective view partly broken away of the poster roller.

Fig. 11 is a side view of a pick-up link.

Fig. 12 is a front view of Fig. 11.

Fig. 13 is a side view of a retarding link.

Fig. 14 is a front view of Fig. 13.

Fig. 15 is a side view partly in section and partly broken away of the poster roller.

Referring to Figs. 1 to 4 the display device comprises a metal housing 1 having two sides 10—10, a top 2, bottom 3, a removable front 4 and a back 5. The housing when closed, offers a substantially dust-proof protection for the operating parts of the device, all of which fall within the 10 housing.

The front 4 comprises a vertically hinged frame 6 provided with a window 7 of transparent material, for instance of glass, the dimensions of which correspond to those of the displays. If 15 desired the frame 6 may be an ornamental frame, but I prefer to provide a plain metal frame for the housing proper and provide a separate ornamental frame which covers either only the front or also partly or fully the sides of the housing.

The sides 10—10 are tied together at the top by rods 11 and 11' and at the bottom by rods 12 and 12', the rods being secured to the sides 10 by means of screws or in other suitable way.

Centrally located with respect to the front and 25 the rear of the casing are an upper and a lower transverse shaft 16 and 17 respectively, carried in suitable bearings 15 provided on the sides 10—10 (see Fig. 4).

Close to each of their ends, each of the shafts 30 16 and 17 carries sprockets 20—20, preferably spaced from the sides 10—10 by suitable washers.

The two left-hand and the two right-hand sprockets 20—20 are interconnected by a pair of synchronized chains 21—21, inside guides 35 22—22 being provided to guide the straight portions of the chains.

Each chain is provided with a pick-up link 23 (see Figs. 3, 11 and 12) the two pick-up links being provided on corresponding portions of the 40 tow chains to form a complementary pair. The pick-up links comprise fixed pawls 24 which extend outwardly from the chain.

Preceding the pick-up links in the direction of travel of the chains are provided one or two 45 pairs of retarding links 25 (see Figs. 3, 13 and 14). The retarding links are provided with a stop 28 and with a pivoted tongue 26 which is normally pressed against the stop 28 by means of a spring 27.

The tongue 26 projects outwardly from the 50 chain and when pressure is exerted on the tongue 26 from its side facing the spring 27 the tongue is pressed against the stop and then assumes the position indicated in Fig. 13 in full lines; however, if pressure is exerted on the tongue from the other side the tongue assumes the position indicated in Figs. 13 and 14 in dotted lines. It should be noted that the tongues 26 of the 55 retarding links 25 are longer than the pawls 24 of the pick-up links 23. The reason therefor will appear later on.

A plate 30 carrying the light source or light 60 sources and also acting as a reflector, is secured to the sides 10—10, the plate 30 being parallel with the front and back of the housing and is disposed intermediate between the two chains 21—21 preferably closer to the back than to the front of the housing. The plate 30 is preferably 65 coated with a light-reflecting coating 31, for instance with a coating of white enamel. The plate 30 carries suitable light sources, for instance, incandescent lamps 34 which are inserted in suitable sockets 32 secured to the plate 30.

In the drawings seven vertically-mounted lamps 70 34 are shown, so spaced as to obtain a substan-

tially uniform illumination of the light transparent display. Electric connections are provided for the lamps through 32 and 33 and the lamp circuits may be suitably controlled by switches or other control means.

For the driving of the sprockets 20 suitable driving means are provided. In the device illustrated two motors M¹ and M² are provided which are vertically mounted on the sides 10—10 above the shaft 17 and centrally disposed with respect to the chains 21—21. The shaft 35 of each of the motors is provided with a worm 36 which matches with a worm gear 37 rotatively carried on a horizontal stud 38 mounted on the corresponding side 10 (see Fig. 4). Also rotatively carried on the stud 38 and fixedly connected with the worm-gear 37 is a driving member 39 adapted to drivingly engage the teeth of the corresponding sprocket 20.

The driving member 39 comprises a disc 40 carried by a bushing 42 and a disc 40' carried by a bushing 43, both bushings being rotatively provided on the shaft 38. The discs 40 and 40' are fixedly interconnected by a plurality of rollers 41 shaped to engage the teeth of the sprocket 20. The driving member 39 is fixedly connected with the worm-gear 37 by means of a retaining washer and a screw 45. Thus the worm-gear 37 and the driving member 39 rotate in unison and act as intermediate driving means between the motor 95 work 36 and the sprocket 20.

It should be well understood that other suitable driving means could be used to drive the sprockets.

The sides 10—10 carry inwardly facing complementary U-shaped channels 50—50 forming loops surrounding the chains 21—21 and acting as guiding runways or tracks for the display carriers as will be later explained.

Each track 50 comprises two straight portions 51 and 51' provided at the front and at the rear of the sides 10—10 along and outside of the chains 21—21, these straight portions extending substantially the whole length of the display window 7. It should be noted that, for reasons later to be explained, the front portions 51 and rear portions 51' of the track are not symmetrically disposed with regard to the chains, but the front track portions 51 are slightly closer to the chains 21—21 than are the rear portions 51'.

The straight portions 51 and 51' of the tracks are interconnected by upper and lower curved track portions 52 and 52', which are substantially circular but which slightly close toward the front. Preferably the curved track portions 52 and 52' are composed of two circular portions 53 and 54, and 53' and 54' respectively drawn around different centers. Starting from the rear straight track portion 51' the upper portion 53 and lower portion 53' follow for about 135° circles drawn around the centers of the shafts 16 and 17 respectively, these portions being thus concentrical with the sprockets 20.

The curved portions 54 and 54' which connect the portions 53 and 53' with the straight front track portion 51 extend approximately 45° and are drawn around centers 55, which fall outwardly and to the rear with respect to the centers of the shafts 16 and 17. Thus the track portions 54 and 54' fall closer to the chains 21—21 than the track portions 53 and 53'.

For the insertion of the display units, I provide in the front track portions 51, suitable openings 56—56 in Fig. 1, which are normally covered by flat spring members 57—57 and which can be raised for the insertion of the display units.

5 My display device is suitable for various types of displays, for instance for the display of panels carrying pictures, printed matter, or the like, and these panels may be standard posters of paper or of other transparent flexible material, and for the sake of simplicity the display members will be referred to hereafter as posters.

10 I prefer to subject the posters to a suitable treatment to enhance their transparency to light, for instance, colored paper posters may be treated with a suitable oil whereby not only their transparency to light is increased, but also their colors rendered more vivid.

15 The poster 85 which consists of a transparent panel carrying a picture, advertising matter or the like, and has the proper dimensions for which the display window is designed, is provided at its lower end, as shown in Fig. 9, with a reinforcing member in the form of a crimped metal strip 89. 20 At its upper end, as shown in Fig. 8, the poster is provided with a metal shield 86, crimped at 88 around the end of the poster and forming there-with a hooked portion 87.

25 The poster is detachably secured to a carrier member, which will hereafter be described, and which together with the poster form the display unit.

30 The carrier comprises a bar-shaped member 60 (see Figs. 5 to 7) provided at its rear side with a stiffening angle bar 61. At both of its ends the bar 60 is provided with rectangular openings 72—72, which serve, as will be later explained, for the engagement of the pick-up and retarding links 23, which during their travel before the display window engage by means of their pawls 24, 35 the upper edges 73 of the openings 72.

40 On its four corners the carrier 60 is provided with cylindrical guides 62, by means of which the carrier is guided in the tracks 50. The guide cylinders are preferably made of fibre or are provided with a fibre sleeve.

45 The bar member 60 carries rearwardly extending triangularly-shaped brackets 63 and 64 respectively. At the top portions the brackets 63 and 64 are provided with holes 69 forming bearings for the pivots 71 of an idler-roll 70, whereas at their lower rear end the brackets 63 and 64 are provided with a bearing 68 and a slot 65 respectively to receive the pivot 97 and the extension 96 50 of a roller 95 (Fig. 10). The extension 96 is rectangular and the bearing 65 of the left-side bracket 63 has a corresponding shape (see Fig. 7). A leaf spring 66 having a rectangular opening 67 corresponding in shape to the extension 96 retains 55 the same in place.

60 The roller 95 as shown in Figs. 10 and 15, consists of a hollow cylinder 100, and is provided with end-pieces 101—101, properly secured thereto. A plug 105 is fixedly disposed within the cylinder at a suitable distance from its left end.

65 A rod 103 provided at one end with the rectangular projection 96 and on its other end with a stud 108 is rotatively supported in the left end piece 101 and in a bearing 107 of the plug 105 respectively.

Surrounding the rod 103 is a coil-spring 102 anchored with its ends 106 to the plug 105 and with its other end 104 to the rod 103.

70 The roller 95 is provided with a transversal recess 98 adapted to receive the reinforced end 89 of the poster 85.

To assemble the display unit the roller 95 is inserted with its pivot 97 in the opening 68 of bracket 64 and with its projection 96 in the slot 66 of bracket 63, and is so retained by the slotted

leaf-spring 66. It should be well understood that if desired the roller may be permanently secured to the brackets 63 and 64 as the insertion and removal of the posters takes place without the removal of the roller 95 from the brackets.

80 The roller 95 is given the desired tension by winding up its spring 102 through rotation of the roller to a predetermined extent; it will be apparent that while the cylinder 100 rotates with its pivot 97, the projection 96 is fixedly held in the slot 66 of the bracket 63 and the spring 102 is thus given the desired tension, which is also imparted to the roller 95.

85 With the roller 95 held under the proper tension and in a position in which the recess 98 is accessible, the reinforced end 89 of the poster 85 is passed from the top through the gap formed between the bar 60 and the guide roll 70, and then inserted in the recess 98. The roller 95 is released and assumes a position in which the spring 102 is partly unwound and in which the poster 85—except for its hooked end portion 87, which extends beyond the carrier 60 and idler-roll 70—is wound around the roller 95.

90 To insert a unit in the display device its guide 100 cylinders 62 are forced through the openings 56 of the tracks 50, passed by the springs 57. Upon the insertion of both pairs of its guide cylinders 62 the unit is guided in the tracks 50.

95 The individual units are interconnected by engaging with the free hooked end 87 of each poster 85 the upper edge of the carrier bar 60, of the adjoining unit. If, as is the case in the device shown, the poster is secured to its roller 95 by means of its lower end, its free upper end is hooked to the carrier bar of the next unit in advance, (see Figs. 5 and 6). However, if the upper end of the poster is secured to its roller, the free lower end of the poster will be hooked to the carrier next in the rear. Thereby on a poster, in 110 any position of its unit, two forces are exerted, first the pull exerted on its one end (in the present case the lower end) by its tensioned roller 95, this pull tending to wind up the poster on its roller; secondly, the pull exerted on the other end 115 (in the present case on the upper end) of the poster by the carrier of the adjoining unit (in the present case the unit next in advance) which pull tends to unroll the poster.

120 The resulting force on the poster and the extent to which the poster is unwound in the different positions of the unit during its travel along the tracks thus depends in this case on the distance between its carrier and the carrier next in advance and this distance in its turn is determined by the 125 interlocked operation of various parts of the mechanism and will be more fully explained in connection with the description of the operation of the display device.

130 Pivotally mounted on the two lower front rods 12 are catches 81 biased by springs 83 and carrying cams 82, and pivotally mounted on the upper front rods 11 are catches 77 carried by levers 75 and biased by springs 78. The function of the catches 77 and 81 and the cams 82 will be explained 135 in the operation of the device.

140 To insure that the posters as they appear before the display window be free from folds and wrinkles, I provide a plurality of slanted straightening levers 90 pivoted at 91, and disposed at the two sides of the display window, which rest with slight pressure on the poster appearing before the window, and keep it taut. Proper stops 92 are provided to limit the movement of the levers 90.

145 The operation of my display device will now be 150 described:

The individual display units are inserted in the device, as has been previously explained, by passing their cylindrical guides 62 through the spring-covered openings 56—56. So inserted the unit is 5 guided in the tracks 50—50 by means of its four guide cylinders 62—62. To tie together the successive display units, the projecting hooked end 87 of each poster 85 is attached to the top edge of the bar member 60 of the unit next in advance, as 10 has been explained in connection with Figs. 5 and 6.

Thus in Fig. 3, which represents the left side of the display device, and in which the advance of the chain is shown to be in clockwise direction, 15 so that the display units advance upwardly through the display space, the free end of the poster of the unit A—2 is hooked around the bar 60 of the unit A—1; the free end of the poster of unit A—3 is hooked around the bar 60 of the unit 20 A—2, etc.

After the display units have been so tied together, the motors are started which causes the sprockets 20—20 to drive the chains 21—21 at a constant speed. The chains carry with them the 25 twin pick-up links 23—23 and one or two pairs of retarding links 25.

As has been stated before, the straight front portions 51 of the tracks and the upper and lower curved portions 54—54', which are excentrical with respect to the sprockets 20—20, are closer to the chains than are the straight rear portions 51' and the curved portions 53—53' which are concentric with the sprockets. The pawls 24 of the pick-up links 23 are of such length that they 35 may engage the apertures 72 of a carrier-bar 60 when such apertures are encountered by the pawls 24 in their travel on the excentrically located portions 54 and 54' and the straight front portion 51 of the tracks, but not when the pawls 24 travel 40 along rear front portion 51', and the curved track portions 53 and 53'.

When the pick-up links 23 in their travel along the lower track portions 54' reach the cams 82 their pawls 24 force the cams 82 out of their way 45 and thereby free from the catches 81—81 the carrier bar 60 of a display unit which then assumes the position shown in Fig. 3 to be occupied by the display unit A—3. The pawls 24 at the same time engage the openings 72 of the bar 60 of this unit 50 and this bar is now carried upwardly by the pick-up links 23. The carrier bar 60 of this unit passes before the display window and after that passes the catches 77.

When the links 23—23 assume the position indicated in Fig. 3 their pawls 24 disengage the apertures 72 of the carrier bar 60 of a unit which then 55 occupies the position shown in the drawings to be occupied by the unit A—2. The carrier bar 60 of this unit is prevented by the catches 77 from dropping back, which engage the lower edge of its bar 60. The pick-up links 23 now proceed with the chains without their pawls further engaging any of the carrier bars until the links 60 again ascend in the lower front curved portion of the tracks and after pushing aside the cams 82, as before described, engage the bar 60 of the following display unit, which in the meantime has 65 assumed the position indicated in Fig. 3 as being occupied by the unit A—3.

In Fig. 3 the display device is shown at a moment at which the pawls 24—24 of the pick-up links 23—23 are just about to disengage the carrier of the display unit A—2 after having carried 70 same past the display window 7. The unit A2 is 75 retained in this position through the engagement

of the lower edge of its bar 60 by the catches 77—77 and remains in this position for almost a full revolution of the pick-up links.

In this position of the display unit A—2, the poster 85 of the succeeding display unit A—3, 80 which by means of its hooked end 87 engages the locked carrier of the display member A—2, and of which the carrier 60 is locked by the catches 81, appears fully unrolled in front of the display window.

The poster 85 of the unit A—3 remains thus displayed in its stretched condition, until the pick-up links 23—23 have again reached the position in which their pawls 24—24 first cause the catches 81—81 to release the bar 60 of the display unit 90 A—3, and then engage the apertures 72—72 of this carrier.

As the carrier 60 of unit A—3 moves upwardly, it causes poster 85 of unit A—3 to gradually disappear by re-rolling around its roller 95, and the 95 poster 85 of the unit A—4 to gradually rise before the display window by unrolling from its roller 95 which with its carrier 60 is now retained by the lower catches 81—81.

It should be noted that the carrier of unit A—4 100 has assumed the position previously occupied by the unit A—3, partly due to the pull exerted on its poster 85 by the advancing carrier of unit A—3, and partly due to the pressures exerted by the weight of the succeeding units A—5, A—6, etc. 105 piled up in the lower portion of the tracks.

As the carrier of the display unit A—3 thus advances and the poster 85 of the unit A—4 gradually unrolls before the display window taking the place gradually given up by the poster 85 of unit 110 A—3, it appears to the onlooker as if the poster 85 of the unit A—3 would stand still and the poster 85 of unit A—4 would gradually rise in the front of it.

As the carrier of unit A—3 passes with its upper 115 guide cylinders 62—62 the catches 77 it abuts against the guide cylinders 62—62 of the preceding unit A—2 and being still in engagement with the pawls 24 of the pick-up links 23—23, it pushes the carrier of A—2 forward along the track and 120 this in turn pushes the carrier of the preceding unit A—1.

The unit A—1 thereby comes to fall with its center of gravity on the descending portion of the track, being however checked in its fall by its 125 engagement with the tongues 26 of the retarding links 25, which are carried by the chains 21—21 in proper spacing relative to the pick-up rings 23—23.

If desired more than one pair of retarding links 130 may be provided, although as a rule a single pair suffices.

As has already been previously stated, the retarding links 25 are so constructed that in the ascending portion of the tracks their tongues 26 135 are free to retract when passing the carriers 60 and thus do not engage or otherwise interfere with same.

The display units pile up in the lower curved portion of the track and depending on their number also partly or fully fill up the straight rear track 51'.

The number of display units provided in the device can vary within comparatively wide limits. For instance, in the display device shown in the 140 drawings twenty units can be provided. In the case of the device being provided with a maximum number of display units the whole track loop is filled with units, except for that portion of the track which opposes the display window and for 145

one interspace corresponding to a carrier unit.

On the other hand, as has been stated, it is not necessary to fill up the display device to its maximum capacity, and in the device illustrated satisfactory operation is obtained even if the number of units is reduced to six. This feature is of great practical importance as the number of posters to be displayed may be conveniently reduced or increased without affecting in general the operation of the device.

While I have described a specific embodiment of my invention, it should be well understood that various modifications may suggest themselves without departing from the spirit of the invention, and that more or less of the novel features of my invention may be combined in the display device.

I do not wish, therefore, to be limited to the specific example shown, but desire the appended claims to be construed as broadly as permissible in view of the prior art.

What I now claim as new and desire to secure by Letters Patent is:

1. A display unit comprising a roller, a carrier for said roller, a spring to bias said roller, said spring being anchored with one end to said roller and with its other end to said carrier, and a poster detachably secured with one end to said roller and having its free end passing between the carrier and the roller and means to project said free end of the poster beyond said carrier and said roller.

2. In a display device comprising a casing, a plurality of display units within said casing, each unit comprising a carrier and a spring-biased roller and a poster detachably secured with one end to said roller and adapted to roll up on same, the free end of each poster being detachably secured to the carrier of one of the adjoining units.

3. A display device comprising a casing, complementary guide tracks provided on the two sides of the casing, a plurality of display units, each unit comprising a carrier and guides by means of which the units are guided in said tracks, and a poster, said poster at one end being spring-biased to its carrier and at its other end being attached to one of the adjoining units, and means cooperating with said carriers to successively move said units along said track.

4. A display device comprising a plurality of display units each comprising a bar member, and an endless chain adapted to travel at constant speed, a member on said chain adapted in certain positions of the chain to engage the bar member of a selected unit and to pass the bar members of the units in other positions of the chain without engaging same and a second member on said chain adapted in certain positions of the chain to engage the bar member of another selected unit and to pass the bar members of the units in other positions of the chain without engaging same.

5. A display unit comprising a display opening, a looped track and a looped chain disposed within said track and closely encircled by same, a plurality of display units guided in said track, the distance between said track and said chain being smaller in the region of the display opening than in the other portions of the track, said chain carrying a member which is adapted to engage said display units only in the region of said display opening.

6. In a display unit, a display space, a plurality of individual display units detachably interconnected with each other, a chain and a member carried by said chain adapted to successively en-

gage said display units to lift them through said display space and to disengage said units after they have passed said space, and another member carried by said chain to cause retarded falling down of the display units after they have passed the display space.

7. A display device comprising a housing having a display opening at the front and closed looped tracks on its two sides, looped chains disposed inside of said tracks adjacent to the two sides of the housing and closely spaced to said tracks, driving means including a motor to rotate said chains at a constant speed, said means being encircled by the said tracks and said chains, interlocked display members guided in said tracks, means comprising locking members and pawled links carried by said chains to successively move said members along the track and to cause their arrested display before the opening.

8. A display device comprising a housing, a display space and a plurality of display units, each comprising a carrier bar, a roller secured to said carrier bar and being spring-biased thereto, a poster detachably secured with one of its ends to said roller and adapted to wind around same, said poster having its free end detachably secured to the carrier bar of one of the two adjoining units, said interconnected units thereby forming a closed elastic band in which part of the display units are fully wound around their roller, and means to cause the unrolling from its roller of a poster when it passes the display space.

9. In a display device, a housing having a display space, a closed looped track, a looped carrier chain disposed substantially in parallel to said track and means to drive said chain, a pick-up member on said chain, a plurality of detachable display units, each unit comprising a carrier and guides to guide it in said track, a spring-biased roller mounted on said carrier and a poster secured with one of its ends to said roller and adapted to wind around the same, the poster having its free end detachably connected to the carrier of one of the adjoining units, said pick-up member adapted to engage successive units and lift them through the display space and to disengage said units after they have passed the display space.

10. In a display device a housing comprising a display window provided in the front of said housing, driving means disposed in said housing, two sidewise disposed looped chains and looped tracks surrounding said chains, a plurality of display units guided in said tracks, a pair of opposite members, one on each chain, and adapted to move with said chains to engage a unit when it approaches said window and to disengage said unit after it has passed said window, and a second pair of opposite members, one on each chain, and adapted to engage a unit when it enters the rear portion of said housing and to disengage said unit when it leaves said rear portion.

11. A display device having a housing, a display window and a closed looped track, said track consisting of straight front and straight rear portions and upper and lower curved portions, and a plurality of individual spring-biased display units interconnected with each other to form an elastic band, said units adapted to individually pass before said display window in the front straight portion of the track, the other portions of the track being at least partly occupied by display units, and means to cause the intermittent advance of the display units and their successive passage and arrest before the display window.

12. In a display device, a looped track, a plurality of removable display units, each comprising as a unitary structure, a carrier, guides, a spring-biased roller, and a poster secured with one of its ends to said spring-biased roller and tending to wind around said roller, said display units being adapted to be moved along said track and being guided therein by their guides, a display window in the front of said device, said display units being interlocked with each other by interconnecting the free end of each poster with the carrier of the adjacent unit, said posters assuming in different portions of the track a condition which varies from being fully wound around its roller, to being fully unrolled depending on the distance between the carriers to which its two ends are secured, the posters forming an elastic endless band and being adapted to successively unroll before said display window, and means cooperating with said display units to positively engage one of the carriers and thereby cause intermittent advance of the band.

13. In a display device comprising a casing and a display window on the front of said casing, a driving mechanism disposed at the two sides of the casing and sidewise with regard to said window, each of said mechanism comprising a motor, a chain and gear members connecting said motor with said chain, and a shaft interlocking the two mechanisms.

14. A display unit comprising a casing having

a window, a plurality of display units within said casing, each comprising a carrier, an endless track to guide said carrier and an endless chain closely encircled by said track, and two lug members carried by said chain, one of said lug members having a fixed pawl to engage said carriers for the upward movement of the units past the window, and the second of said lug members having a retractable pawl and adapted to said carriers for the retarded lowering of the units in the rear portion of the casing.

15. A display unit comprising a carrier including a bar member, guide cylinders at the two ends of said member, brackets secured to said member close to the two ends thereof, a roller pivoted in said brackets, a poster secured to said roller, and a spring which biases said roller and causes the poster to wind up around said roller.

16. In a display device comprising a housing and closed looped tracks secured to the two sides of the housing, a plurality of display units removably disposed in said housing, each comprising a carrier and guide members at the two ends of said carrier to guide said carrier in said tracks, a spring-biased roller secured to said carrier and a poster connected with one end to said spring-biased roller and having at its free end a hook-shaped bar to secure said poster to the carrier of the adjoining unit.
